Des. 242,221
Patented Nov. 9, 1976

242,221

COMBINED PRESSURIZED CONTAINER AND DISPENSING CAP THEREFOR

Ernst Claes Kare Allvarsson Lonegren, 2 Ravstigen,
Saltsjö Duvnäs, Sweden

Filed Dec. 11, 1974, Ser. No. 531,499

Term of patent 14 years

Int. Cl. D9—01

U.S. Cl. D9—9

FIG. 1

FIG. 2

FIG. 3

FIG. 4

FIG. 5

FIG. 6

FIG. 7

FIG. 1 is a perspective view of a combined pressurized container and dispensing cap therefor showing my new design;

FIG. 2 is a perspective view with the cap inverted;

FIG. 3 is a top plan view of the cap;

FIG. 4 is a bottom plan view of the cap;

FIG. 5 is a side elevational view of the cap;

FIG. 6 is a side elevational view of the cap looking from the right of FIG. 5; and

FIG. 7 is a side elevational view with the cap inverted.

I claim:

The ornamental design for a combined pressurized container and dispensing cap therefor, as shown.
